US0D1080357S

(12) **United States Design Patent** (10) **Patent No.:** **US D1,080,357 S**
(45) **Date of Patent:** **** Jun. 24, 2025**

(54) **LEASH LOCK**

(71) Applicant: **GEM Products, LLC**, Jacksonville, FL (US)

(72) Inventor: **Elliot Vainer**, Jacksonville, FL (US)

(73) Assignee: **GEM Products, LLC**, Jacksonville, FL (US)

(**) Term: **15 Years**

(21) Appl. No.: **29/904,041**

(22) Filed: **Sep. 29, 2023**

(51) **LOC (15) Cl.** 09-06

(52) **U.S. Cl.**

(57) **CLAIM**

The ornamental design for a leash lock as shown and described.

DESCRIPTION

FIG. 1 is a first perspective view of an embodiment of a leash lock;

FIG. 2 is a top view of the leash lock of FIG. 1;

FIG. 3 is a front side view of the leash lock of FIG. 1;

FIG. 4 is a bottom view of the leash lock of FIG. 1;

FIG. 5 is a rear side view of the leash lock of FIG. 1;

FIG. 6 is a first side view of the leash lock of FIG. 1;

FIG. 7 is a second side view of the leash lock of FIG. 1; and,

FIG. 8 is a second perspective view of the leash lock of FIG. 1.

Any components in the appended drawings shown in broken lines are for illustrative purposes only and form no part of the claimed design.

1 Claim, 8 Drawing Sheets
